J. R. REECE

SHUTTLE FEELER THREAD PARTER OPERATING MECHANISM

Filed Dec. 5, 1927

UNITED STATES PATENT OFFICE.

JAMES R. REECE, OF SALISBURY, NORTH CAROLINA, ASSIGNOR TO DRAPER CORPORATION, OF HOPEDALE, MASSACHUSETTS, A CORPORATION OF MAINE.

SHUTTLE-FEELER THREAD-PARTER-OPERATING MECHANISM.

Application filed December 5, 1927. Serial No. 237,640.

This invention relates to filling replenishing looms and is more particularly directed to the shuttle feeler thread parter which is usually employed in such looms to part the outgoing filling between the shuttle and cloth selvage.

It is now the usual practice to provide replenishing looms with a shuttle feeler thread parter, or parter and clamp, which acts upon the outgoing filling end on replenishment of filling to part the filling between the cloth selvage and shuttle. In some cases the parter, or parter and clamp, carried by the shuttle feeler, has been actuated to perform its parting function only upon replenishment of filling, in order that upon failure of replenishment the filling will not be parted, which might result in imperfect cloth.

Where the parting, or parting and clamping, mechanism has been actuated only on replenishment of filling, it has been common to provide a train of mechanism actuated through the replenishing operation to operate the parter or parter and clamp and, in case of failure of replenishment, to fail to part the filling. These mechanisms as heretofore devised have usually introduced complicated parts at a portion of the loom where the parts are already much crowded, and many attempts have been made to simplify the train of mechanism for causing actuation of the parter or parter and clamp only on replenishment of filling.

One of the important features of the present invention consists in a simplified means for actuating the parter or parter and clamp only when replenishment is effected. More specifically stated, the parter or parter and clamp in accordance with the present invention is mounted on the shuttle feeler and the transerrer has secured thereto a parter closing member preferably constituted as an arm secured to the transerrer or a part thereof and having a rearwardly extending end portion normally positioned above the parter or parter and clamp when the latter is in its operating position, the effect being that when the transerrer effects replenishment of filling the parter or parter and clamp will be actuated to part the thread between the cloth selvage and shuttle, but should the transerrer fail to effect replenishment the parter or parter and clamp will not be actuated, so that perfect cloth will continue to be woven.

The invention and new features thereof

will best be made clear from the following description and the accompanying drawings showing a good practical form thereof.

In the drawings:

Fig. 1 is a perspective view of parts at the 60 replenishing side of a loom provided with the present invention;

Fig. 2 is a side elevation of one form of 65 parter or parter and clamp which may be advantageously employed in connection with the present invention parts of the loom being in section; and

Fig. 3 is a side elevation showing the 70 parter or parter and clamp as being actuated by the closing member when replenishment of filling is effected a part of the lay being in section.

Looms of the replenishing type are now 75 usually provided with a hopper for containing the filling carriers to be transferred from time to time to the shuttle when replenishment of filling is indicated by the indicating means. The indicating means for calling 80 into operation the replenishing mechanism is not shown herein throughout its details because it is now well understood in the art and may comprise any usual form of detecting means, such, for instance, as a feeler mechanism or the like.

The loom frame 1 may be of usual construction and, as shown in the present instance, is provided with a bracket 2 having a guide 3 for the shuttle feeler 4 as it is moved towards and from the front of the loom. The shuttle feeler 4 is pivotally supported on a pin or dead shaft 5 which may be conveniently carried by the bracket 2, and extending laterally from the shuttle feeler is a stud 6 which is engaged by the bifurcated end of the arms 7 and 8 which are themselves associated with the usual transverse or change shaft. It has not been deemed necessary herein to show the transverse or change shaft and its manner of actuation because these details are now of common knowledge.

In the present instance of the invention, the shuttle feeler 4 is shown as provided with a thread parter and clamp of usual construction for parting and clamping the filling between the cloth selvage and shuttle and carrying the clamped end frontwardly to position the end leading to the cloth selvage for the action of the temple thread cutter. If desired the clamping feature for the thread may be omitted, but it is preferable to provide

the thread clamp for the purposes above indicated, and the present invention will be described in connection with a thread parter and clamp.

5 The thread parter and clamp, comprising the parting member 9 and the cooperating clamping member 10, is pivotally mounted upon the stud 11 projecting from the shuttle feeler 4 and, as shown in Fig. 2, the parter 10 and clamp are indicated in their open position with the shuttle feeler moved rearwardly to its operating position, and the parts so far described may be of usual construction.

Extending from the parter 9 is a pin 12 15 which is adapted to be engaged by a trip device 13 mounted upon an upstanding arm 14 secured to a part of the bracket 2. The trip device may be of usual construction as now common in looms of this type and may act 20 as heretofore to open the thread parter and clamp as the shuttle feeler moves rearwardly to feeling position and to trip by the pin 12 when the shuttle feeler is moved frontwardly, so that the parter and clamp remain closed 25 in front position to hold the end leading to the cloth selvage for the action of the temple thread cutter. All these parts as thus far described may be of usual or any preferred construction.

30 Mounted on the loom frame is the hopper stand 15 which may be of any usual type, but as herein shown is adapted to support a rotary hopper, as usual, containing the filling carriers 16. These parts may be of ordinary 35 construction.

Mounted in a bearing 17 on the hopper stand is the stud shaft 18 on which is preferably mounted the transferrer 19, from the hub portion 20 of which is the downwardly 40 extending arm 21 having pivotally connected thereto at 22 the usual dog 23 adapted to be engaged by a bunter on the lay, as usual, when filling replenishment is indicated. In the present instance, the dog 23 has the laterally 45 extending pin 24 which is connected by the arm 25 to the shuttle feeler 4, the construction being such that on call for replenishment of filling the dog 23 will be moved into the position indicated by Fig. 3 for engagement by 50 the bunter 26 mounted upon the lay, as usual.

All of the parts as hereinbefore described 55 may be of usual construction as may also be the lay 27, which is provided with the usual shuttle box 28 at the replenishing side of the loom.

As hereinbefore stated, the thread parter and clamp is opened by the trip 13 as the shuttle feeler moves backwardly to its shuttle feeling position, and the parting member 60 9 is provided with a hump or rising portion 29 which extends above the top of the shuttle feeler 4 when the parter and clamp is opened ready for its parting and clamping action.

In accordance with the present invention, 65 means are provided of simple and effective

construction for actuation by the transferrer when it performs its transferring function, so that on call for replenishment of filling the parter and clamp may be actuated to part and clamp the thread, provided only 70 that filling replenishment is actually accomplished.

The parter closing member is constituted as an arm which is secured to a part of the transferrer and has the laterally and rearwardly extending portion, the terminal end of the latter being normally positioned above the parter and clamp when the latter is in its parting and clamping position.

As shown in the present instance of the invention, the parter closing member comprises an arm 30 having a rearwardly extending securing portion 31 which projects through an opening formed in the downwardly extending member 21 of the transferrer, and such portion 31 of the closing member is adjustably secured in place by a set screw or bolt 32 whereby the bodily position of the parter closing member may be adjusted towards and from the front of the loom to properly position the parter closing member for the performance of its function. The portion 31 of the parter closing member extends frontwardly, as indicated in Figs. 1 and 2, and its front portion is turned laterally, as at 33. Extending backward from the portion 33 of the closing member is the arm 34, the rear terminal end portion of which at 35 may be projected laterally, indicated in Fig. 1, in order to present a sufficient engaging portion to act upon the parter. Since the parter closing member is fixed or secured to the transferrer or the rigid downwardly extending arm 21 thereof, it follows that during normal weaving operations the parter closing member will be maintained in its raised position, as indicated in Fig. 1, with the terminal end portion 35 thereof in position to act upon the parter when the transferrer effects replenishment of filling, as indicated in Fig. 3. Since the parter closing member is secured to the transferrer or a part thereof and the transferrer itself is pivotally supported on the stud 18, it follows that when the transferrer moves downwardly and effects replenishment of filling, the terminal end portion 35 of the parter closing member will descend upon the projection 29 of the parter and cause the parter to be closed to part and clamp the thread.

Preferably the parter closing member is formed of resilient material, as, for instance, elastic wire, which may yield appropriately under continued movement of the transferrer after the parter closing member has closed the parter and clamp, and while the present invention is not necessarily limited to the parter closing member as formed of a single piece, as indicated in the present illustration of the invention, yet the simplicity of the

single piece parter closing member lends itself favorably to the accomplishment by a simple means of the results sought by a more complicated mechanism.

5 The adjustability of the parter closing member in its connection with the transfferer or the downwardly extending arm 21 thereof affords a simple and convenient means for positioning the terminal end portion 35 of 10 the parter closing member to act effectively upon the desired portion of the parter during replenishment.

It will be noted from the disclosures of the present invention that the means for actuating the parter and clamp to part and clamp the thread is not only directly associated with the transfferer, but presents a simple and effective means for operating the parter and clamp only when filling replenishment is effected. Should filling replenishment not be effected, the transfferer of course will not descend to its full transferring position, with the result that the parter closing member will 20 itself not descend.

25 Since the parter closing member is secured directly to the transfferer or its downwardly extending arm 21, the lateral extension 33 serves to position the backwardly extending portion 34 at the side of the hopper with the end 35 of the parter closing member properly positioned above the parter for action thereupon when and only when filling replenishment is effected.

What is claimed is:

35 1. In a filling replenishing loom, the combination of a hopper, a pivotally mounted transfferer having a downwardly projecting arm provided with an opening from front to rear thereof, a dog pivotally connected to said arm for operating the transfferer, a shuttle feeler having a thread parter, a parter closing member constituted as an arm having a backwardly extending securing end engaged in said opening of the downwardly projecting arm and provided with a lateral bend terminating in a backward extension with its terminal end portion above the parter when in parting position to close the parter when filling replenishment is effected.

40 2. In a filling replenishing loom, the combination of a hopper, a pivotally mounted transfferer having a downwardly extending arm, provided with an opening the longitudinal axis of which is towards and from the

front of the loom, a dog pivotally connected to said arm for operating the transfferer, a shuttle feeler having a thread parter, a parter closing member constituted as a single arm having a backward extension which is engaged in said opening of the downwardly extending arm of the transfferer and extending laterally and backwardly from said arm with its terminal end portion above the parter when in parting position to close the parter when filling replenishment is effected, and means for adjusting the parter closing member in said opening of the downwardly extending arm of the transfferer.

3. In a filling replenishing loom, the combination of a hopper, a pivotally mounted transfferer having a downwardly extending arm having a through opening from front to rear, a dog pivotally connected to said arm for operating the transfferer, a shuttle feeler having a thread parter, and a parter closing device constituted as a single bent member having an end directly engaged in said through opening of the downwardly extending arm of the transfferer and having a frontwardly and laterally bent portion provided with a backward extension, the terminal end of which is above the parter when the latter is in its operating position that it may act upon and close the parter on replenishment of filling.

4. In a filling replenishing loom, the combination of a hopper, a pivotally mounted transfferer having a downwardly extending arm provided with a through opening extending from front to rear below the transfferer, a dog pivotally connected to said arm for operating the transfferer, a shuttle feeler having a thread parter, and a parter closing device constituted as a single resilient member having a backwardly extending securing end passed into said opening of the downwardly extending arm of the transfferer and having a laterally projecting portion provided with a backward extension, the terminal portion of which is above the parter when the latter is in its rearward position that it may act to close the parter on replenishment of filling and a set screw for fastening the securing end of the closing device in adjusted position in said through opening.

In testimony whereof, I have signed my name to this specification.

JAMES R. REECE.
